C. L. PECK.
AIR CONTROL DEVICE FOR GAS ENGINES.
APPLICATION FILED JULY 8, 1916.

UNITED STATES PATENT OFFICE.

CHARLES L. PECK, OF CHICAGO, ILLINOIS.

AIR-CONTROL DEVICE FOR GAS-ENGINES.

1,260,571.

Specification of Letters Patent. Patented Mar. 26, 1918.

Application filed July 8, 1916. Serial No. 108,121.

To all whom it may concern:

Be it known that I, CHARLES L. PECK, a citizen of the United States, and a resident of the city of Chicago, county of Cook, and State of Illinois, have invented certain new and useful Improvements in Air-Control Devices for Gas-Engines, of which the following is a specification.

My invention relates to a device for admitting air into the feed manifold of a gasolene engine.

One of the objects of my invention is the provision of an air intake valve that will readily subserve the purposes for which it is designed and at the same time provide means whereby the engine may be primed by feeding a suitable fluid into the feed manifold. Another object of my invention is to provide a device of this character that is capable of adjustment so that the quantity of air passing into the manifold may be controlled and regulated according to the conditions under which the motor is being driven. Another object of my invention is the provision of a control valve that is capable of being adjusted from the dashboard so that the person operating the vehicle need not leave the same in order to make the proper adjustments. As before stated, it is an object of my invention to provide a combined air control valve and a priming device and it is also an object of my invention to permit the priming device to be fed from the dashboard without necessitating the person driving the car to leave the same.

I prefer to accomplish the divers objects of my invention by the means and in the manner hereinafter fully described and as more particularly pointed out in the claims, reference being had to the accompanying drawings forming a part of this specification, wherein,—

Figure 1 is a side elevation of a fragmentary portion of a gasolene engine of a well-known type, showing my device mounted upon the manifold and the operating rod extended through the dashboard of the vehicle.

Fig. 2 is a central vertical section of the valve taken on line 2—2 of Fig. 3.

Fig. 3 is a top plan of the valve portion with the operating stud in section, the view being taken on line 3—3 of Fig. 2.

Referring to the drawings, 5 is the manifold leading from the carburetor 6, to the cylinders of the gas engine 7, and 8 is the

dashboard of a suitable motor vehicle in which said engine is mounted.

Mounted in the manifold 5, by means of a suitable tap pipe 9, is my improved air control valve and priming cup, which preferably comprises a hollow shell 10 of any suitable shape and dimensions, preferably hemispherical or conical, so as to provide a central lower portion of reduced diameter, from which the fluid and air are adapted to be discharged into the pipe 9. In the construction shown in the drawings, I have made this shell 10, of a double hemispherical shape and joined the same together in the manner shown. This, however, is not essential and I do not desire to be limited to the construction shown. The upper portion of the shell is open and is provided with a flared mouth, into which is inserted a plate 11, having a plurality of apertures 12 therein, said plate resting upon a suitable annular shoulder 13 formed upon the interior of the shell. This plate 11 is preferably stationary and superimposed thereon is an upper plate 14, comprising two quadrants joined by an intermediate web, as shown in Fig. 3 of the drawings. After this secondary plate is disposed in proper relation upon the disk 11, a suitable split spring ring 15 is snapped into an annular internal recess 16 formed in the wall of the shell immediately above said quadrant plate, so as to retain the same in position and prevent their accidental removal.

The quadrant plate 14 is adapted to be rotated upon disk 11 so as to close any portion of the apertures 12 in the disk 11, and in order to do this I provide the intermediate web of the plates 14, with a hollow stud 17, the upper portion whereof is enlarged and knurled to provide a hand-grip 18, should occasion arise to use the same, and the stud is extended above said hand-grip and provided with a hollow boss or hub 19. A suitable hollow rod or tube 20 extends from the dashboard of the vehicle downwardly and forwardly toward the valve and it is connected with the boss 19 by means of a flexible hollow shaft 21, so that by rotating the rod 20 inside the dashboard, the quadrant plate 14 may be rotated to the proper position to cover the desired number of apertures in disk 11. Inside the dashboard is a suitable dial 22 and an index-hand or pointer 23 is secured to the extended end of 110

the rod 20 so that the relative position of the quadrants of the plate 14 may be determined by the operator in the vehicle without leaving the car and raising the covering 5 hood over the engine. The extended portion of the rod 20 inside the dashboard is slightly enlarged to provide a cup 24, having a knurled cap 25, closing the same, so that a suitable priming fluid may be injected there-
10 in and pass down through the rod 20, the flexible shaft 21, and into the boss 19 disposed on the top of the quadrant plate. A suitable hollow stem 26 extends down from the open portion of the boss 19 through the 15 plate and disk and into the chamber of the shell 10. A coiled expansion spring 27, surrounding this hollow stem, is held in position by suitable washers and a pin 28 tapped transversely through said stem. As will be
20 understood, the priming fluid after reaching the boss 19, will pass through the top of the valve, through the hollow stem 26 and drip into the lower portion of the shell 10, where it will be discharged through the pipe 9 into
25 the manifold 5 of the motor. In order to prevent dust, sand and small particles of foreign matter passing through the openings in the disk 11 and reaching the carburetor of the engine, thereby causing inconvenience
30 and necessitating adjustment, I prefer to place a quantity of steel or glass wool 29, or other suitable material, in the bottom of the shell 10 in order to not only strain the priming fluid that may be injected into the de-
35 vice, but also to filter the air passing through the control valve into the manifold.

While I have herein described and illustrated certain instrumentalities for carrying out my idea, it, of course, will be obvious to others skilled in the art, that modifications thereof may be made without materially departing from the spirit of my invention, as, for example, the valve shell may be made of conical shape or shape like the 40 ordinary pet-cock, or in lieu of the steel wool, a strainer gauze may be placed in a convenient position inside of the shell 10, and divers means may be employed to rotate the quadrant plate or the disk 11 may be ro-
45 tated and the quadrant plate retained in stationary position. I therefore desire it understood that all such modifications or changes are contemplated as included within the scope of my invention as set forth in the
50 55 appended claims.

What I claim is:—

1. In combination with an internal combustion engine for motor vehicles, an auxiliary air intake valve, and means extended to and operable from the dashboard of said vehicle for controlling said valve, said means adapted to transport priming fluid from said dashboard to said valve.

2. A combined air control valve and primer for gas engines for motor vehicles comprising a shell open at one end and provided with a discharge orifice, a duct leading from the dash-board of the vehicle to said shell whereby priming fluid is adapted to be discharged into said shell, a plate in the open end of said shell and provided with perforations, and a movable quadrant plate coacting with the first-mentioned plate and operable from the dash-board of the vehicle whereby the adjustment of said movable plate is adapted to uncover perforations in said closure plate.

3. A combined air control valve and primer for gas engines for motor vehicles comprising a shell open at one end and provided with a discharge orifice, means supplying priming fluid to said shell from the vehicle dash-board, a perforated plate adjacent the open end of said shell, and a rotatable plate coacting with said perforated plate whereby the quantity of air entering said shell therethrough is increased or diminished.

4. A combined air control valve and primer for gas engines for motor vehicles comprising a shell open at one end and provided with a discharge orifice, a duct leading from the dash-board of the vehicle to said shell whereby priming fluid is adapted to be discharged into said shell, a plate disposed in the open end of said shell and provided with a plurality of radiating series of perforations upon opposite sides of the axis of said plate, and a rotatable quadrant plate coacting with said perforated plate whereby the adjustment of said rotatable plate is adapted to uncover predetermined series of perforations in said closure plate.

Signed at Chicago, county of Cook and State of Illinois, this 5th day of July, 1916.

CHARLES L. PECK.
